UNITED STATES PATENT OFFICE.

WILLIAM FREDERICK MANGELS, OF BROOKLYN, NEW YORK.

GUN-MOUNT.

1,321,657.

Specification of Letters Patent. Patented Nov. 11, 1919.

Original application filed April 2, 1918, Serial No. 226,222. Divided and this application filed June 8, 1918. Serial No. 239,021.

To all whom it may concern:

Be it known that I, WILLIAM F. MANGELS, a citizen of the United States, and a resident of the city of New York, Coney Island, 5 borough of Brooklyn, in the county of Kings and State of New York, have invented a new and Improved Gun-Mount, of which the following is a full, clear, and exact description, this being a division of the application for Letters Patent for a machine-gun for shooting-galleries, Serial No. 226,222, filed by me April 2, 1918.

The object of the invention is to provide a new and improved gun mount for machine 15 guns for shooting galleries arranged to limit the pointing movement of the gun to prevent damage to the side walls, ceiling or floor of the establishment or injury to bystanders. Another object is to counterbalance the gun with a view to enable the user 20 to readily move the gun about for aiming purposes.

With these and other objects in view, the invention consists of certain novel features 25 of construction as hereinafter shown and described and then specifically pointed out in the claims.

A practical embodiment of the invention is represented in the accompanying drawings forming a part of this specification, in 30 which similar characters of reference indicate corresponding parts in all the views.

Figure 1 is a side elevation of the machine gun;

Fig. 2 is an enlarged sectional rear elevation of the same on the line 2--2 of Fig. 1;

Fig. 3 is an enlarged sectional plan view 40 of the same on the line 3--3 of Fig. 1 and showing more particularly the means for limiting the sidewise swinging movement of the gun;

Fig. 4 is an enlarged sectional side elevation of the machine gun with parts in position for firing; and

Fig. 5 is a sectional front elevation of 45 the same on the line 5--5 of Fig. 4.

The frame 20 of the machine gun is provided with a suitable gun stock 21 and a barrel receiver 22 in which is held a barrel 23. On the frame 20 is mounted to rotate 50 intermittently a magazine 32 adapted to hold cartridges 45 adapted to register with the bore of the barrel 23 and adapted to be successively fired by a firing pin 50 controlled by a hammer 106 actuated by a cam

wheel 111 secured on a shaft 73 adapted to be turned by a crank arm 80. The shaft 73 is journaled in bearings 74 and 75 formed on the frame 20.

In order to permit the user to swing the gun around during the firing operation with the object of hitting different targets in the shooting gallery, use is made of a gun mounting arranged as follows: A base 130 is attached to a suitable stand at the front 60 of the shooting gallery, and in this base is held a vertically adjustable sleeve 131 adapted to be raised or lowered and fastened in place by clamping the upper end of the base around the sleeve 131. For this purpose the upper end of the base 130 is provided with a vertical slit 132 and lugs 133 and 134 arranged on opposite sides of the slit and engaged by a clamping screw 135 which when loosened permits up and down 65 movement of the sleeve 131. When the desired adjustment of the sleeve 131 has been made the clamping screw 135 is screwed up to clamp the sleeve in place in the upper end of the base 130. In the upper end of the 70 sleeve 131 is mounted to turn a cylindrical neck 140 depending from a head 141 resting on the top edge of the sleeve 131. The head 141 is provided on opposite sides with bearings 142 and 143 in which are mounted to 75 turn the trunnions or bearings 74 and 75 previously mentioned and formed on the sides of the casing 20. The lower end 145 of the frame 20 is made cylindrical with the axis coinciding with that of the shaft 80 73, and on the bottom of this lower end 145 of the casing 20 is arranged a pivot 146 engaged by the eye 147 of a rod 148 extending downward in the neck 140. A spring 150 is coiled on the rod 148 and is seated 85 with its upper end on a flange 151 formed on the head 141, and the lower end of the spring 150 rests on a washer 152 seated on a nut 153 screwing on the lower end of the rod 148. By the arrangement described the 90 spring 150 exerts a downward pull on the casing 20 to hold the bearings 74 and 75 in firm contact with the bearings 142 and 143 so that the frame 20 is counterbalanced and may be swung upward or downward to any 95 desired position. The up and down swinging movement of the frame 20 is limited by stop screws 160 and 161 screwing in the head 141 and adapted to be engaged by opposite sides 100 of the eye 147 to limit the swinging move- 105 110

ment of the frame 20 in either direction thus preventing the user of the gun from pointing too far upward or too far downward to avoid hitting the ceiling or floor 5 of the shooting gallery by the bullets. It will be noticed that the stop screws 160 and 161 can be screwed farther in or farther out to correspondingly increase or diminish the up or down swinging movement of the frame 20, and the said stop screws 160 and 161 are provided with jam nuts 162 and 163 to lock the stop screws in place after the 10 desired adjustment has been made according to the size of the gallery. It will also be noticed that the head 141 is mounted to turn in the sleeve 131 and in order to limit this turning movement of the head, use is 15 made of stop screws 165, 166 screwing in lugs 167, 168 formed on the upper end of 20 the sleeve 131. The inner ends of the stop screws 165 and 166 are adapted to be engaged by a lug 169 attached to or forming part of the head 141. It will be seen that by the arrangement described the turning 25 movement to the right or the left of the gun is limited by the lug 169 abutting against either of the inner ends of the stop screws 165 and 166, and the latter may be screwed in or screwed out to increase or 30 decrease the range of the turning movement of the gun, and when the desired adjustment has been made the stop screws are locked in place by jam nuts 170 and 171. It is understood that by the arrangement 35 described the user of the gun is not liable to point the gun too far in a sidewise direction for the bullets fired by the gun to strike the side walls of the shooting gallery.

In order to hold the neck 140 of the head 40 141 from being lifted out of the sleeve 131, use is made of set screws 175 screwing in the sleeve 131 and engaging an annular groove 176 formed in the peripheral face of the neck 140.

45 Having thus described my invention, I
claim as new and desire to secure by Let-
ters Patent:—

1. A machine gun for shooting galleries, comprising a base, a vertically adjustable concave head carried by the base and mounted to turn, a gun frame mounted to oscillate on the head and having a cylindrical lower end fitting in the concavity of the head, said frame being provided with a stock and a barrel, a spring connection be-

tween the cylindrical end of the gun frame and the head, a magazine mounted on the gun frame and coaxing with the barrel, means for limiting the oscillating movement of the gun frame, and means for limiting the turning movement of the head. 60

2. In a gun mount, a base, a vertically adjustable member carried by the base, a concave head mounted to turn in the member, a gun frame mounted to oscillate on the head and having a cylindrical lower end fitting in the concavity of the head, and a spring connection between the cylindrical end of the gun frame and the head. 65

3. In a gun mount, a base, a sleeve vertically adjustable in the base, a head mounted to turn in the sleeve, adjustable means for limiting the turning movement of the head in the sleeve, a gun frame, means for pivotally connecting the gun frame with the head, a spring connection between the gun frame and head, and adjustable means for limiting the oscillating movement of the gun frame on the head. 70 75

4. In a gun mount, a base, a head having 80
a concave upper end and bearings at oppo-
site sides, the head being provided with a
neck turning in the base, a gun frame hav-
ing a cylindrical lower end fitting in the
concavity of the head and provided with 85
trunnions engaging said bearings, a rod piv-
oted to the cylindrical portion of the gun
frame and extending into the neck of the
head, and a spring on the rod and seated
on said head. 90

5. In a gun mount, a base, a head having a neck mounted to turn in the base, a gun frame mounted to oscillate on the head, a rod pivoted to the gun frame and extending into the neck of the head, a spring on the rod and engaging with its upper end the head, and oppositely arranged screws in the head and adapted to engage the said rod. 95

6. In a gun mount, a base, a sleeve adjustably mounted in the base, and provided with oppositely arranged lugs, a head mounted to turn in the sleeve and having a lug projecting between the lugs of the sleeve, screws in the lugs of the sleeve and adapted to engage the lug of the head, a gun frame, means for pivotally connecting the gun frame with the head, and a spring connection between the gun frame and head. 100 105

WILLIAM FREDERICK MANGELS.
